US00D933611S

(12) **United States Design Patent** (10) **Patent No.:** **US D933,611 S**
Maranto (45) **Date of Patent:** ** *Oct. 19, 2021

(54) **ELECTRICAL RECEPTACLE WITH IN-LINE POWER UNIT**

(71) Applicant: **Group Dekko, Inc.**, Garrett, IN (US)

(72) Inventor: **Vincent Maranto**, Fort Wayne, IN (US)

(73) Assignee: **Group Dekko, Inc.**, Garrett, IN (US)

(*) Notice: This patent is subject to a terminal disclaimer.

(**) Term: **15 Years**

(21) Appl. No.: **29/723,868**

(22) Filed: **Feb. 11, 2020**

CLAIM

The ornamental design for an electrical receptacle with in-line power unit, as shown and described.

DESCRIPTION

FIG. 1 is a perspective view of an electrical receptacle with in-line power unit showing my new design;

FIG. 2 is a left side view thereof;

FIG. 3 is a front view thereof;

FIG. 4 is a right side view thereof;

FIG. 5 is a back view thereof;

FIG. 6 is a top view thereof; and

FIG. 7 is a bottom view thereof.

In the drawings, the broken lines are for the purpose of illustrating environmental subject matter and portions of the article that form no part of the claimed design.

1 Claim, 7 Drawing Sheets
